CLAIM

The ornamental design for an alarm console, as shown and described.

DESCRIPTION

FIG. 1 is a front perspective view of an alarm console showing my new design, with the antenna broken away to indicate indeterminate length;

FIG. 2 is a top plan view thereof;

FIG. 3 is a bottom plan view thereof;

FIG. 4 is a left side elevational view thereof, with the antenna shown in a lowered position, with the broken lines showing for illustrative purposes only and forming no part of the claimed design;

FIG. 5 is a rear elevational view thereof;

FIG. 6 is a front elevational view thereof.

Fig. 1.

Fig. 2.

Fig. 3.

Fig. 4.

Fig. 5.

Fig. 6.
